(57) **CLAIM**

The ornamental design for an electric outlet cover plate, as shown and described.

DESCRIPTION

FIG. 1 is a perspective front view of an electric outlet cover plate showing my new design;

FIG. 2 is a perspective back view thereof;

FIG. 3 is another perspective back view thereof;

FIG. 4 is a front view thereof;

FIG. 5 is a back view thereof;

FIG. 6 is a side view thereof;

FIG. 7 is a side view thereof;

FIG. 8 is a top view thereof;

FIG. 9 is a bottom view thereof;

FIG. 10 is a perspective front view of an alternative embodiment of the electric outlet cover plate;

FIG. 11 is a perspective back view of the embodiment of FIG. 10;

FIG. 12 is another perspective back view of the embodiment of FIG. 10;

FIG. 13 is a front view of the embodiment of FIG. 10;

FIG. 14 is a back view of the embodiment of FIG. 10;

FIG. 15 is a side view of the embodiment of FIG. 10;

FIG. 16 is a side view of the embodiment of FIG. 10;

FIG. 17 is a top view of the embodiment of FIG. 10; and,

FIG. 18 is a bottom view of the embodiment of FIG. 10.

The broken lines in the drawings depict portions of the electric outlet cover plate that form no part of the claimed design.
